TRAVELING CASE

Ernest Norbert Kennedy, London, England

Application November 18, 1938, Serial No. 241,269
In Great Britain November 23, 1937

3 Claims. (Cl. 190—41)

This invention is for improvements in or relating to hand wardrobe trunks, suitcases, traveling cases and the like for containing folded garments, hereinafter referred to generally as cases, comprising attachment means for engagement by the hook of a garment hanger for use with a garment to be folded, and garment-folding means comprising or constituted by a garment-folding element adapted to be moved upwards from a lower position behind a part of the garment situated outside the case to an upper position in the case for folding the garment.

In cases heretofore intended for accommodating women's dresses, a hanger bar for carrying garment hangers which support garments folded into three sections by means of crossbars has been secured to the top of the case.

The present invention has for its main object to provide an improved construction of a case which shall facilitate folding garments, such as men's suits, into two without creasing them, and inserting the folded garments into the lid or body of the case which is neat in appearance and conforms substantially with the appearance of luggage, e. g. suitcases, commonly in use at the present day.

According to the invention, a case of the type described has the attachment means provided in the lower part of the lid or body of the case. This attachment means may be a hanger bar along which the hook of a garment hanger can slide. This position of the hanger bar facilitates garments, such as men's suits, (coat, waistcoat and trousers) on garment hangers hooked to the hanger bar, being folded into two and packed in the case.

The hanger bar and/or supports for the crossbar or like element may be detachably mounted in the lid or body of the case instead of being fixed therein.

Two supports for the crossbar or like element may be in the form of rails, each spaced a short distance away from the top and adjacent side wall of the lid or body of the case, and preferably extending in the form of a horizontal loop beyond the front edge of the top of the open lid or body, respectively.

The crossbar preferably has at its ends crooks arranged to be suspended from said supports and formed with abutments to limit endwise movement thereon, the middle portion of the crossbar preferably being cranked downwards.

The hanger bar preferably has the shape of a U having a longer limb situated alongside or

vertically above a shorter limb, and the closed end of the U situated outside the front edge of the bottom of the lid or body of the case, for the purpose later described herein.

It is to be observed that the crossbar or other garment folding element, when supported in the upper part of the case, and the hanger bar or other attachment means are attached or adjacent to relatively opposite walls of the case.

A carrying handle may be provided attached to the outside of that relatively parallel wall of the case to which the crossbar or other garment folding element is adjacent when in its upper position.

In some cases a hanger bar may be provided in the upper portion of the lid or body of the case for carrying garments to be folded into three by means of a crossbar or like element used for folding into two garments supported by the hanger bar in the lower part of the case.

At least one indicating or positioning member may be provided for use in placing the garment-folding element in such a position in relation to the garment that when moved upwards into the body or lid of the case, the garment will be folded therein.

The garment-folding means may be constituted by a frame movably attached to the case and adapted to be extended from it behind the unfolded garment, the free end marginal portion or edge of which frame constitutes the garment-folding element which is positioned by the body or sides of the frame.

Other forms of garment-folding means comprising at least one indicating or positioning member are described hereinafter.

One embodiment of the invention and modifications thereof are diagrammatically illustrated by way of example in the accompanying drawing, wherein:

Figure 1 is a front elevation showing one form of case according to the invention, its lid having been removed.

Figure 2 is a vertical section taken on the line 2—2 in Figure 1, and

Figure 3 is a horizontal section taken on the line 3—3 in Figure 1, the lid being shown in broken lines;

Figure 4 shows a crossbar used in the case; Like reference characters designate like parts throughout the several views.

Referring to the drawing, the case comprises a body portion 10 that is open at the front and can be closed by a lid 12, both of which parts 55 may be made of fabric lined, compressed or vul-

canised fibre, leather, canvas or any other suitable material (rigid or flexible) from which suitcases may be made. The body portion 10 has a base 14 on which it can be supported when being packed with garments hereinafter referred to as suits), a rear wall 15, two side walls 16, 17 and a top wall 18 having a handle 19 and locks 20 to receive hasps on the lid 12. The bottom of the lid 12 carries metal lugs which, when the lid is closed, enter into metal sockets 25 on the under-surface of the base 14.

Attachment means in the form of a flat metal hanger bar 26, 27 of U-shape for carrying the hooks 28 of garment hangers 29 is provided in the lower part of the case close to the bottom thereof. The longer limb 26 of this hanger bar lies above the base 14 and has its rear end portion 30 riveted to the rear wall 15, while the shorter limb 27 lies below the limb 26 and is bent sideways towards the wall 16 and is riveted to the upper face of the base 14 near its front edge 31. Alternatively, the hanger bar may have its limbs lying in the same horizontal plane parallel with the base 14. The closed end 32 of the U-shaped hanger bar is situated outside the front edge 31, as shown most clearly in Figures 2 and 3. The purpose of this arrangement is that when the body portion 10 of the case is supported vertically, a coat hanger 29 carrying a suit shall hang vertically below the front edge of the base 14 of the case. If desired, the suit can extend flat horizontally in front of the case when about to be folded.

Two supporting members 34, 35 in the form of rails for carrying a garment-folding element constituted by a crossbar or the like are secured in the upper part of the case close to the top wall 18 thereof, but spaced a short distance below the latter and from the adjacent side wall. Each of these rails has its rear end portion 38 riveted to the rear wall 15, and has its front portion bent to form a loop 39 having a laterally bent end portion 40 riveted to the underside of the top 18 close to its front edge.

As shown in Figures 1 to 3, a crossbar 36 has its end portions bent to form two crooks 43, each having a hook 44 at its free end. Further, the central portion 46 of the bar is cranked downwards so that the weight of a suit hanging over the bar will be carried principally at the sides where the bar is higher, the centre of the suit sagging into the lower or downwardly cranked section. Cranking the bar has the further advantage of strengthening it and allowing a lighter material to be used. When such a crossbar is placed transversely behind the middle of a suit with its crook embracing the sides of the suit which may hang freely downwards or may be laid out flat horizontally, and the crossbar is then moved upwardly by hand, the suit will be folded into two by the crossbar which can then be readily placed on the loops 39 of the rails 34, 35 and then slid into the body of the case towards the rear wall 15 thereof. The hooks 44 on the crossbar 36 constitute abutments and limit the end-wise movement of the crossbar when it is carried by the rails. A second, third or subsequent suit

of men's clothes can be folded similarly into two each by a separate crossbar and placed into the case. If desired, cross-straps, preferably extensible, may be stretched from side to side of the case and secured in position across the garments when they have been placed in the case.

In some cases a modified crossbar 136 shown separately in Figure 4 may be used. This crossbar 136 is square-ended to provide rectilinear limbs 131 to rest on the rails 34, 35, and has a downwardly-cranked portion 146. If desired, the crossbar 36 or 136 or some other form of garment-folding element may have more than one downwardly-cranked portion.

Two pockets 56, 57 may be provided on the base 14, one at each side of the hanger bar, if desired, into which hair-brushes, shaving tackle, underwear, or the like may be packed.

Various modifications may be made in the details of construction described above without departing from the invention.

I claim:

1. A case for the reception of at least one folded garment, comprising a lid and an open-fronted body, a hanger bar for supporting the hook of a garment hanger, said hanger bar being disposed adjacent to that wall of the body which serves as a base upon which the body may rest with its open front vertical and unobstructed during packing, and extending rearwardly from at least as far forward as substantially the front edge of said body, the forward section of said bar being so fashioned with respect to the front edge of said body so that a garment hanger may hang downwardly outside said body when said lid is in an unobstructing position and when said body is rested on the edge of a support, and so that the garment hanger may thereafter be turned around and slid back into said body, said downward part of the hanger being adapted to support a garment outside said body in a freely downward extending position, and a garment-folding element adapted to be manually moved upwards from a lower position behind the middle of said freely hanging garment so situated outside said case to an upper position to bring said garment and garment hanger into a packing position within said open front body in which said garment extends upwardly from said garment-hanger, over said garment-folding element, and then downwardly upon itself, and means in the upper portion of said body detachably engageable with said garment-folding element for holding the same in place.

2. A case according to claim 1, wherein said hanger bar has one end projecting beyond the front edge of said body, said end being of J-shape, and one limb of said J being directly above the other.

3. A case according to claim 1, said means in the upper portion of said body comprising rails parallel to the wall opposite that wall which serves as a base when said case is being packed, said rails extending in the form of horizontal loops beyond the front edge of said portion of said body.

ERNEST NORBERT KENNEDY.
